(57) **CLAIM**

The ornamental design for a storage receptacle, as shown and described.

DESCRIPTION

FIG. 1 is a perspective view of a new and ornamental design for a storage receptacle;

FIG. 2 is a front elevation view of the storage receptacle shown in FIG. 1;

FIG. 3 is a rear elevation view of the storage receptacle shown in FIG. 1;

FIG. 4 is a left side elevation view of the storage receptacle shown in FIG. 1;

FIG. 5 is a right side elevation view of the storage receptacle shown in FIG. 1;

FIG. 6 is a top plan view of the storage receptacle shown in FIG. 1; and,

FIG. 7 is a bottom plan view of the storage receptacle shown in FIG. 1.

Contour lines represent character and contour only and do not illustrate material, surface ornamentation, or surface decoration. Broken lines show extraneous features that form no part of the claimed design.

1 Claim, 7 Drawing Sheets
